Application August 1, 1933, Serial No. 683,202

1 Claim. (Cl. 81—53)

This invention relates to speed wrenches and has for the primary object the provision of a device of the above stated character which is of the socket type and equipped with means for rapidly turning on and off a nut of a bolt and having means of the ratchet type whereby maximum leverage may be had on the nut for starting the nut off of the bolt or for turning the nut tightly home on the bolt.

10 With these and other objects in view this invention consists in certain novel features of construction, combination and arrangement of parts to be hereinafter more fully described and claimed.

15 For a complete understanding of my invention, reference is to be had to the following description and accompanying drawing, in which

In the drawing:

Figure 1 is a vertical sectional view illustrating a speed wrench constructed in accordance with my invention.

Figure 2 is a sectional view taken on the line 2—2 of Figure 1.

Figure 3 is a similar view taken on the line 25 3—3 of Figure 1.

Figure 4 is a similar view taken on the line 4—4 of Figure 1.

Referring in detail to the drawing, the numeral 1 indicates a ratchet wrench, the chuck 2 there- 30 of receiving a socketed element 3 to fit a nut. The wrench 1 is equipped with a laterally extending operating lever 4 having a ratchet drive with the chuck. The lever carries an angularly related finger piece 5. The chuck 2 operated by the lever 35 4 will be capable of turning a nut tightly upon a bolt or for releasing a nut which is tight upon a bolt. Extending from the chuck 2 and in align-

ment therewith is a stem 6 adapted for fit within a chuck 7 of a screw driver 8 of the reversible worm feed type. After the nut has been released on the bolt by the turning of the lever 4, said nut may be then rapidly turned off of the bolt 60 by reciprocating the screw driver 8. Also a nut may be turned rapidly onto a bolt by reversing the action of the screw driver 8, the reversing button of the screw driver being shown at 9. Thus it will be seen a tool has been provided 65 wherein a nut may be rapidly turned on or off of a bolt and also whereby considerable leverage may be had on the nut when desiring to tighten or loosen the nut upon the bolt.

While I have shown and described the preferred 70 embodiment of my invention, it will be understood that minor changes in construction, combination and arrangement of parts may be made without departing from the spirit and scope of my invention, as claimed.

Having described the invention, I claim:

A tool comprising a chuck-like body having an annular groove, a handle arranged at right angles to the body and having one end enlarged to provide a casing-like portion receiving a portion of 80 the body and overlying the groove, a set screw carried by the casing-like portion and extending into the groove, a reversible ratchet means between the handle and the body, a finger piece secured to the other end of said handle and ar- 85 ranged at right angles to the latter, a shank integral with the body and extending through one end of the casing-like portion of said handle and arranged at right angles to the handle, and a reversible worm feed type screw driver con- 90 nected to the shank.
